EXPRESSION CONTROL FOR ELECTRICAL MUSICAL INSTRUMENTS.

1,183,244.

Specification of Letters Patent.

Patented May 16, 1916.

Application filed June 26, 1907. Serial No. 380,987.

To all whom it may concern:

Be it known that we, MELVIN L. SEVERY, of Arlington Heights, county of Middlesex, and Commonwealth of Massachusetts, and 5 GEORGE B. SINCLAIR, of Medford, county of Middlesex, and said Commonwealth, both citizens of the United States, have made certain new and useful Improvements in Expression Control for Electrical Musical Instruments, of which the following is a specification.

This invention pertains to that class of musical instruments wherein magnetically attractive sonorous bodies are vibrated by 15 means of electromagnets having properly timed electric pulsations delivered thereto; and the object of our invention is the construction of means for controlling the volume and loudness of the music produced by 20 the instrument. We set forth in this case a type of our invention in which the sonorous bodies are metallic strings of the kind usually employed in musical instruments.

One of the essential features of our invention comprises a permanent individual loudness control operating to voice the individual tones of the musical gamut, and consisting of specially wound electromagnets for the actuation of the strings, so 25 adapted that the attractive energy of each magnet is proportioned to the peculiar conditions of its associated string or strings, to the end that the instrument shall be correctly voiced.

Another feature of our invention consists 35 in changing at will the voltage of the current which energizes the electromagnets, and thereby varying the amplitude of vibration of their associated strings.

In certain co-pending applications we 40 have shown, described and claimed features which are illustrated and described in the present application, but which are not herein claimed, and in other co-pending applications we have broadly claimed the art of 45 producing musical tones, which art is involved but is not claimed in the present application. All matters set forth and claimed in co-pending applications filed in our 50 names, or in the names of either of us, and not specifically claimed herein, are expressly saved and reserved for one or another of such applications. Among these may be

noted our joint applications Serial No. 273,199, filed August 7, 1905; Serial No. 55 377,571, filed June 6, 1907; Serial No. 379,714, filed June 19, 1907; Serial No. 537,257, filed January 10, 1910; Serial No. 740,201, filed January 4, 1913; Serial No. 753,018, filed March 8, 1913; and Serial No. 754,475, filed March 15, 1913.

Referring to the drawings forming part of this specification, Figure 1 is a perspective diagrammatic view of a musical instrument embodying our invention. Fig. 2 is a detail plan view of the magnet rail and its adjusting devices. Fig. 3 is a diagram illustrative of the pedal operated octave coupler, and of certain types of variable resistances used in connection with the instrument.

The sonorous bodies, which are shown in the drawings as magnetically attractive strings 1, are vibrated by means of electromagnets 10, to which properly timed electric pulsations are delivered upon the depression 75 of the keys 3. The means for producing the properly timed pulsations consists of a source of electric current, and make-and-break devices comprising uniformly rotated toothed disks 12 and brushes 13 contacting 80 therewith.

The circuit between the generator 40 shown in Fig. 1, and the electromagnets 10 comprises the wire 16, brush 14, shaft 11, disks 12, brushes 13, and wires 39; the return from said electromagnets 10 embracing 85 the wires 26, contacts 25, brushes 24 of such keys as are depressed, wire 59, (where the keys depressed are treble ones), brush 96, contact 97 (where the octave coupler bar 90 90 is in the position shown in Fig. 1) wire 100, brush 53, contact 51, wire 62, resistance 60, wire 61 to the proper armature brush of the generator 40. The return circuit for the bass electromagnets will embrace wires 26, 95 contacts 25, brushes 24, wire 58, brush 55, contact 50, wire 52, contact 51, wire 62, resistance 60, and wire 61 back to said armature brush. If, now, a key 3 is slightly depressed, its brush 24 will be put into touch with a contact 25, and the current will traverse the resistances 28, 28^a, and the short connecting wires 29, 29^a to the wire 26, and thence to the electromagnet associated with the same. This gives a greater resistance to 10 the current than is received when said brush

is raised into touch with the contact 25^a, and hence only one resistance 28^a is traversed; while the elevation of the brush to the contact 25^b short circuits all such resistances, 5 and gives the full strength of actuating current to the electromagnet associated therewith. If desired, additional contacts and resistances may be employed, and thus give a still finer degree of differences. This gives 10 the player a control approximating as closely as may be desired to that of the ordinary piano, as far as delicacy of touch is concerned.

Our first-mentioned loudness-control is 15 produced by winding the electromagnets 10 in accordance with our discovery that the resistance of such windings should be inversely proportional to the frequency of the vibrations. The theory underlying this is that the 20 more rapidly a string vibrates,—reaching for the upper notes about two thousand per second,—, the more the self-induction of the windings and the magnetic lag of the iron core of such electromagnet will interfere 25 with the flow of the current, and consequently the less strongly the magnet will be actuated. In other words, the amount of current which will flow through an electromagnet when the current is continuous, will 30 be far greater than the amount which will flow when the current is rapidly interrupted; the strength of the magnet's attraction being found to diminish as the rapidity of interruption is increased. Hence to produce 35 theoretical uniformity in magnetic attraction on the part of all the electromagnets of the gamut, such electromagnets should be wound with wire of diminished resistance as the scale is ascended. In some 40 cases we find it sufficiently satisfactory to use the same size of windings for several electromagnets; the heaviest sizes of wire being for the upper treble magnets, the finest being for the low bass, and the intermediate 45 magnets having windings of medium sized wires; although we show in the drawings only three such groups of windings, it is evident that any desired number may be used. Further, owing to the amplitude of 50 the bass strings' vibrations and their consequent liability of striking their electromagnets, such electromagnets must be adapted for a strength of attraction which will permit them to be located at a greater distance 55 from the strings; one sufficient to avoid the danger of such striking while at the same time properly actuating the strings. By thus constructing the electromagnets associated with the different strings so that 60 the attractive force of each magnet shall be proportioned to the peculiar conditions of its string, we make an important advance in the proper voicing of the instrument.

Another method of voicing the strings 65 consists in so proportioning the distance of

the electromagnets 10 from their respective strings that all the latter shall be actuated with equal sonorous effect. Economy would naturally suggest locating the magnets as near as possible to their strings, but other conditions determine how near they can be placed. The upper treble strings being of limited vibrational excursion, can have their electromagnets located close thereto without danger of contact. At the same time, because of their slight mass and high tension, 70 their magnets must be very close thereto in order to properly actuate them. On the other hand, the low bass strings, because of their large mass and inertia, need to have 75 their electromagnets located as near to them as is consistent with the danger of contact above referred to; but of course not so near as are the upper strings to their magnets. Moreover, the upper strings act so slightly 80 upon the sounding board of the instrument that they must be more energetically vibrated than are the others; thus still more needing closeness of proximity between them and their magnets; while the low 85 bass strings by their superior mass or weight, and a consequently more vigorous vibration of the sounding board, do not require to be as close to their magnets as do the upper strings. The intermediate strings, 90 on the other hand, on account of their less mass than the lowest strings, and less tension than the highest strings, and their consequent easier actuation, taken in connection with the increased effective current-actuation 95 owing to their less rapid current-interruption, need to have their electromagnets located farther away from them in order to maintain substantial equality in sonorous effect with the strings both above and below 100 them. This feature of our invention is illustrated by Fig. 2 which shows the electromagnets at the right hand end of the magnet rail 70 to be located much closer to their strings 1 than are the electromagnets at the 105 extreme left hand, or bass end; while the electromagnets in the vicinity of the point 71 on said rail, are farther away from their strings 1 than are the bass magnets. Said point of maximum distance we find to be 110 about one third up from said bass end. While the electromagnets may be permanently fixed in their positions relative to their strings, we prefer to have them capable of movement at will toward and from 115 the latter in order to provide the player with another means for varying the loudness of music produced. This can only be done, however, by some means which will move the intermediate magnets more than the 120 others, and the most practical way in which this can be accomplished is by jointing the magnet rail at the point 71, and also hinging the ends of the same at 75 and 76, and adapting the rail to be angularly moved by 125 130

devices under the control of the player. This is most important, for, were the magnet-rail to be moved through a series of positions each parallel with the other, a movement sufficient to affect an upper treble string would give no appreciable alteration to others; and a movement away from the strings sufficient to reduce slightly the strength of vibration of the intermediate 5 strings, would be enough to render the upper treble strings or even the low bass strings practically mute. Moreover, other natural laws come in play which must be considered in adjusting the magnet-rail. In the first 10 place the upper treble strings are so fine and so close to their electromagnets that they do not appreciably come under the law of inverse squares, but mainly under that of the magnetic shell, the strength of attraction 15 varying almost directly as the distance. Consequently, the upper electromagnets can be given a greater range of adjustment than would be the case under the law of inverse squares; but the electromagnets being normally very close to their strings, such adjustment must be slight.

The intermediate electromagnets, owing to the greater mass of the strings and their distance from them, act mainly under the 20 usual law of inverse squares; and the bass electromagnets being slightly nearer their strings than are the intermediate ones, but not so close as the upper electromagnets, act under a different combination or permutation 25 of the two laws. It is therefore an evidently difficult task to shift the magnet-rail at will, and still accurately preserve the relative sonorous effects upon all the strings of the scale. To this end, several details 30 are essential; that the pivotal point 75 of the treble end of the magnet-rail be not too far from the upper-most string; that the pivotal point 76 be preferably much nearer the lowest string than the highest string, 35 and that the juncture 71 be adjusted toward and from the strings by a pedal, knee-swell or other device adapted to move said juncture so that equal increments or decrements 40 of the pedal will produce equal increments or decrements of sonorous effect. We have discovered that whenever a direct current is 45 broken it becomes practically like an alternating current, and it offers an immensely greater impedance as the breaks become faster. In our case, where the breaks are in a 50 wide variety of periodicities, great care has to be taken to compensate for these, in order that the scale may be even enough for musical purposes. Were we vibrating but one 55 body, as a tuning fork, for example, the only question would be one of efficiency; but it is vastly different for the full gamut of sonorous bodies used in music. The current 60 employed for our instrument is an interrupted direct current, and not an alternat-

ing current. On account of the many factors already referred to it is necessary, in order to produce these results, that equal movements of the pedal shall produce unequal and shifting degrees of motion of the 70 rail. To accomplish the last requirement, the knee-swell 78 is provided with a cam or suitably plotted wedge 77 engaging a rod 74 connected with the lever 72 pivotally supported at 73 and having its short arm joined to said juncture; such wedge or cam being so proportioned that a uniform movement imparted to the pedal 78 will cause a similarly uniform variation in the sound produced.

Another method of expression control, that of changing at will the voltage of the magnet-energizing current, is accomplished by suitably altering the strength of exciter-current, delivered to the field windings of 85 the generator 40. To do this we preferably but not necessarily have the exciter current entirely outside the armature circuit, and introduce into the same a resistance cut in and out by a suitable pedal. The important 90 feature is to provide any means of increasing and diminishing current in the field of the generator, whether external or not. The generator field windings 41 are joined by a wire 42 to one pole of the current source 43, 95 and by a wire 48 to the brush 46 movable by a pedal 47 along a resistance 45 which is joined by a wire 44 to the opposite pole of said current-source. When said pedal is in its elevated position, its brush is in contact 100 with the lower end of said resistance, and so introduces a maximum resistance into the circuit and allows a minimum current to pass to the field magnets. This causes a current of lowest voltage to be generated by 105 the generator 40, and thereby supplies to the electromagnets 10 a minimum intensity of energy. As said pedal 47 is depressed, successive increments of resistance are cut out, with a corresponding increase in exciter-current, in voltage of current generated, and 110 in strength of sound evolved.

Another method of control, that by which we preserve a proper sonorous balance between the various parts of the instrument, 115 is needed in order to overcome the tendency which we have discovered of the bass notes being overbalanced by the treble notes when increased current is delivered to their actuating magnets 10. The means by which 120 we correct this consists of a rheostat 60 adapted to be switched into the energizing circuits to the bass and treble strings by means of a suitable pedal 56, with a constantly larger amount of resistance in the 125 treble circuit than in the bass circuit. In doing this, the pedal 56 is operatively connected with a swinging arm 57 carrying brushes 53, 54, 55 in touch with the two sets of contacts 51, 50. Each of the contacts 51 130

is joined by a wire 62 to a corresponding part of the rheostat 60; while the contacts 50 are joined by wires 52 to an equal number of the contacts 51. The contacts 51 and 50 being each of substantially equal vertical dimension to each other, and the brush 53 being farther from the pivotal center of the arm 57 said brush 53 will sweep over more of the contacts 51 for the same angular movement of said arm, than does the brush 55 over its contacts, with the result that after the arm 57 has been moved to any degree the brush 53 will be in touch with the contact 51 connected with a greater resistance 60 than will be the brush 55. Such dissimilarity in currents we find to be sufficient to equalize the two sections of the instrument, and render them equal in expression however much such expression is varied in the instrument as a whole.

In our method which pertains to means for preventing the abruptness of transition from one number to another number of strings simultaneously sounded, our purpose is to cut less resistance into the treble circuit when the octave coupler is operated, than when it is not used; the bass circuit being unchanged. For we have discovered that although the tones produced by a few simultaneously energized electromagnets will not be materially weaker than the tone produced by a single electromagnet which receives approximately the current previously delivered to the few, yet when the octave coupler throws a considerable number of electromagnets into simultaneous energization, the tones, other things equal, will be sensibly weaker than those produced by a singly energized electromagnet. When, now, the soft pedal 56 is depressed for the purpose of modulating the instrument's expression, and more or less of the resistance 60 is thereby introduced into the circuit, the brush 54 being shorter than the brush 55, more resistance will be switched into the treble circuit than the bass circuit, in the same way as is done by the two brushes 53 and 55. But it will be noted that less resistance is cut into the treble circuit by the brush 54, than is put into the same circuit by the brush 53 when the coupler bar 90 is in its normal elevated position. Hence whenever the coupler bar 90 is depressed a lesser resistance will be cut into the treble circuit than when it is not depressed, through the above described arrangement; and the coupled magnets will be caused to receive sufficient additional current to make up for the loss of energy due to subdivision among the several magnets. When the coupler bar is thus depressed the circuit will include wire 61, topmost wire 62, contact 51, wire 52, contact 50, brush 54, wire 99, contact 98, brush 96, wire 59 to the brushes 24.

Another method of varying the loudness of the instrument is illustrated in Fig. 3, and consists in the introduction of a resistance 80 into the circuit of each electromagnet 10 of the entire gamut, and the provision of a pedal 83 adapted for cutting in and out suitably proportional degrees of all such resistances simultaneously. As shown, the resistances 80 are each connected by a wire 39 to the electromagnets 10, while brushes 81 are joined by wires 84 to the appropriate make-and-break brushes 13. Said brushes 81 are carried by a bar 82 which is moved by said pedal 83, so that when said bar rises through the depression of said pedal all the brushes 81 are made to cut out the proper amounts of resistance and increase the strength of the currents delivered to the electromagnets; thereby increasing and properly modulating the music produced. This is what we term our individual pedal rheostat, and it serves to enable the loudness to be varied in sensibly equal amount for each string, independently of whether one or several strings are simultaneously sounded. A further expression control is also illustrated in Fig. 3, and is one wherein a pedal 87 cuts in or out at will a resistance to the common part of the circuits of all the electromagnets. The resistance 85 shown here is connected at one extremity to the key brushes 24 by means of a wire 88, while said pedal is provided with a brush 86 and is itself connected by a wire 89 to the current source 15. By depressing said pedal, said brush is elevated and made to cut out successive increments of resistance, and thereby to increase the strength of the sound produced. Still another method of expression is obtained by the introduction of a resistance 95 into each of the coupling wires 94 of certain of the coupler brushes 93. Through this arrangement the coupled magnets 10 on the side of the resistance opposite that on which the keys are depressed will be less strongly energized than the magnets upon the same side as the depressed keys; and either the lower strings can be made to predominate over the upper strings, or the upper over the lower, by playing upon the keys associated with the strings desired to thus predominate.

Another exceedingly important element of our musical instrument is that by means of which the electric pulsations delivered to the electromagnets 10 shall be timed with absolute accuracy. The slightest degree less than this renders the instrument a failure as a musical instrument. A variation of one ten-thousandth of a second in the rotation of the make-and-break disks 12, cannot be allowed. Accordingly, a governing device for said disks which can control the same with an accuracy heretofore undreamed of, is not simply desirable, but is

absolutely essential. After years of experimentation, we produced such a governor and applied the same to our electrical musical instruments, with the result of converting them into an unqualified success, 5 where all others were failures. Such a governor is indicated at 111 in Fig. 1 of the drawings forming part of this specification, as controlling and timing the rotation of the disks 12.

10 Although we have described our invention as applied to electromagnetically actuated strings, we do not restrict ourselves thereto, as other types of sonorous bodies 15 may be employed.

15 What we claim as our invention and for which we desire Letters Patent is as follows, to wit:—

1. An electric musical instrument having 20 sonorous bodies of different pitch, electromagnets for their actuation, a source of current, current-pulsating means, and circuits including said source, electromagnets and pulsating means, the circuits associated with 25 sonorous bodies of lower relative pitch being given materially greater resistance than the circuits associated with bodies of higher pitch.

2. An electric musical instrument having 30 sonorous bodies of different pitch, electromagnets for their actuation, a source of current, current-pulsating means, and circuits including said source, electromagnets and pulsating means, the electromagnets associated with sonorous bodies of higher relative pitch being given less resistance than the electromagnets associated with bodies of 35 lower pitch.

3. An electrical musical instrument comprising, in combination, sonorous bodies of 40 different pitch; electromagnets associated with the respective bodies for effecting their vibration; and means for supplying the coils of the respective magnets with pulsations of electric energy differing in frequency for the different magnets, the windings of different magnets offering predetermined resistance differing in degree to compensate for varying impedance offered 45 by said windings incident to varying frequency of pulsation of current therein.

4. A musical instrument comprising magnetically attractive sonorous bodies, electromagnets to which said bodies respectively 50 bear the relation of armatures, and means, including circuits and a source of electrical power, for delivering properly-timed electric pulsations to said electromagnets; said electromagnets being located at differing 55 distances from their sonorous bodies, and including in their circuits resistances which vary inversely proportional to the frequency of said pulsations.

5. A musical instrument comprising tuned 60 sonorous bodies, electro-magnets for their

actuation, and means for delivering properly timed electric pulsations to said electromagnets; the windings of the electromagnets having different resistances, said resistances increasing from the treble magnets to the 70 bass magnets.

6. A musical instrument comprising tuned sonorous bodies, electro-magnets for their actuation, means for delivering properly-timed electric pulsations to said electromagnets, a source of power, and circuits including said source and electromagnets; said circuits having different ohmic resistances, said resistances increasing from the treble 75 magnets to the bass magnets.

7. A musical instrument comprising tuned sonorous bodies, electro-magnets for their actuation, and means for delivering properly timed electric pulsations to said electromagnets; the electromagnets actuating 80 upper sonorous bodies being wound with heavier wire than the electromagnets of the sonorous bodies lower in the scale.

8. A musical instrument comprising tuned sonorous bodies, electromagnets for their actuation, and means for delivering properly timed electric pulsations to said electromagnets; said electromagnets being disposed in a plurality of groups of different 85 windings graded downward from a wire of relatively low resistance, for the highest sonorous bodies, to a wire of relatively high resistance, for the lowest sonorous bodies.

9. A musical instrument comprising magnetically attractive sonorous strings, electromagnets to which said strings bear the relation of armatures, and means for delivering properly timed electric pulsations to said electromagnets; the electromagnets actuating 90 the upper sonorous strings being wound to have a low resistance and being located closer to their strings than the electromagnets farther down the scale.

10. An electrical musical instrument comprising a sonorous body, an electromagnet 110 for its actuation, a rotary pulsation-producing means, a source of current therefor, and means under the control of the operator for varying the amplitude of vibration of said body by gradually varying the voltage 115 of the current generated by said source.

11. An electrical musical instrument comprising, in combination, sonorous bodies and electromagnets for effecting their vibration; a rotary pulsator; a motor for driving said 120 pulsator; a source of electric energy in circuit with the pulsator and electromagnets through branch circuits; means operative at will for varying the voltage of the source of electric energy; and independent means 125 under the control of the operator for varying at will the resistance of the branch circuits containing the electromagnets.

12. A musical instrument comprising, in combination a sonorous body; an electro- 130

magnet for its actuation; a rotary make-and-break device; a source of electric current; means for conveying current from said source to said make-and-break device 5 and to said electromagnet; and means for varying at will the voltage of the current supplied from such source.

13. A musical instrument comprising, in combination, sonorous bodies; electric means 10 for effecting vibration of said bodies; a generator supplying current for said means; an exciter delivering current to the field windings of said generator; and a pedal-controlled rheostat for varying the strength of 15 current delivered by said exciter to the field of the generator.

14. A musical instrument comprising, in combination, sonorous bodies; electric means 20 for their actuation; a generator supplying current to said means; a rotary circuit breaker for producing pulsations in said current; an exciter delivering current to the field windings of said generator; and a pedal-controlled rheostat for varying the 25 strength of current delivered by said exciter to said field.

15. A musical instrument comprising, in combination, a series of sonorous bodies; a source of electric energy a series of electromagnets directly attracting and thus effecting 30 vibration of said bodies, one magnet for each such body; branch circuits each including a magnet of the series means for simultaneously introducing a separate resistance 35 into the circuit of each magnet; and means

for completing the several magnet circuits independently.

16. A musical instrument having strings differing in size and length, electromagnets, and means for delivering electric pulsations 40 thereto for the actuation of said strings, the electromagnets actuating the large and long strings being wound with many windings of relatively fine wire, and the electromagnets actuating the finer and shorter strings being 45 wound with relatively heavy wire.

17. A musical instrument having strings differing in size and length, a magnet rail, and magnets carried thereby for the actuation of said strings, the magnets for the fine 50 and shorter strings being wound with heavier wire than is used for the windings of the other magnets.

18. A musical instrument having strings differing in size and length, a magnet rail, 55 electromagnets carried by said rail, and means for delivering properly timed electric pulsations thereto, the magnets associated with the fine and short strings and also with the long and heavy strings being located 60 nearer to their strings than the magnets associated with the intermediate strings.

In testimony that we claim the foregoing invention, we have hereunto set out hands this 20th day of June, 1907.
